UNITED STATES PATENT OFFICE.

WILLIAM D. PIERSON, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

STOP DEVICE FOR WIRE-DRAWING OR SIMILAR MACHINES.

1,380,412.

Specification of Letters Patent.

Patented June 7, 1921.

Application filed December 1, 1919. Serial No. 341,687.

To all whom it may concern:

Be it known that I, WILLIAM D. PIERSON, a citizen of the United States, residing at Waterbury, in the county of New Haven 5 and State of Connecticut, have invented certain new and useful Improvements in Stop Devices for Wire-Drawing or Similar Machines, of which the following is a specification, reference being had therein to the 10 accompanying drawings.

My invention relates to new and useful improvements in devices for wire drawing or similar machines that will stop the rotation of the wire block whether the same be 15 actuated deliberately or by reason of the operator, the coil of wire or other object becoming entangled and drawn against it.

It is the object of this invention, among other things, to provide a mechanism for 20 this purpose that will be certain in its operation and that will insure the stopping of the block when the operator desires to discontinue such operation or when by reason of accident or inadvertence the wire coil is 25 dislodged or drawn toward the machine or the operator or any other person should by accident be drawn into the machine or should fall against it.

To these, and other ends, my invention 30 consists in the stop device for wire drawing or similar machines, having certain details of construction and combinations of parts, as will be hereinafter described, and more particularly pointed out in the claims.

35 Referring to the drawings, in which like numerals of reference designate like parts in the several figures;

Figure 1 is a plan view of a portion of one 40 form of bench, to which my improved mechanism may be applied;

Fig. 2 is a front elevation thereof; and

Fig. 3 is a transverse sectional view showing some of the details of the mechanism 45 that are associated with and actuated by my invention.

I have adopted for illustrating my invention a type of wire-drawing machine or bench that is shown in Letters Patent, No. 1,025,421, dated May 7, 1912, in which the 50 block and the means for operating it are therein generally disclosed. In this structure the numeral 10 designates the table, supported upon suitable legs 11, that are connected by the front and back angle plates 12 and 13, 14 is the main driving shaft

which is rotating continuously in the journal boxes 15 connected with the legs 11, 16 is the block shaft rotatably mounted in the cap 17 of the journal box 15 and having a beveled gear 18 thereon, the teeth of which 60 mesh into those of a pinion 19 fixed on the shaft 14. The wire block 20 has a make and break connection with the shaft 16, one form of connection mechanism for accomplishing this purpose being shown in the 65 patent above referred to. Said make and break connection mechanism is operated through a collar 21 slidably mounted upon the shaft 16 and connected with the aforesaid mechanism through a pintle 22, the 70 lever 23 pivoted to a fixed part by the pintle 24 and normally held in its up position by a spring 25. A foot treadle 26 is pivoted to a fixed part at 27 and near its outer end passes through an opening 28 in the front 75 plate 29 and connected with the lever 23 through the turn-buckle connection 30. The outer end of the foot treadle 26 is provided with a foot pad 31 for convenience in manipulating it by foot pressure and mounted 80 thereon is a latch 32 which cooperates with a notch 33 in the front plate 29 to hold said lever in a partially depressed position.

In Fig. 3 of the drawings the lever is shown by full lines in its up position, that is, 85 when the make and break connection between block 20 and shaft 16 permits the shaft 16 to rotate while the block 20 may remain stationary or be rotated by manual manipulation if desired, and by dotted lines 90 in its down position, that is the relative position occupied by it when the connection with the block shaft 16 and block 20 is such that the latter rotates with said shaft. This latter is known as the drawing position, at 95 which time the treadle 26 is held under the shoulder 34 by the spring 35 pulling upwardly.

A brake mechanism designated by the numeral 36 to retard the rotation of the 100 block 20 is also operated from this treadle through the turn-buckle connection 37 having connection with the bell crank 38. A partial operation of the treadle 26, so that the latch 32 engages the notch 33, releases 105 slightly the brake pressure upon the block mechanism sufficient to permit the same to be manipulated manually.

The mechanism above described constitutes no part of my present invention and 110

is only shown and described to illustrate the general construction and operation of one form of wire drawing machine to which my invention may be applied, the subject 5 matter of the details thereof being more or less set forth in my co-pending application for Letters Patent designated by the Serial No. 282,399.

The numeral 39 designates the die holder 10 which is pivotally connected at 40 to a swivel block 41 having a pivotal connection with a block 42 by means of the pintle 43. The outer end of the die holder terminates in the usual hook 44, against which is the 15 die 45 held in place by the hand screw 46.

In operation, when the treadle 26 is in engagement with the shoulder 34 the wire block 20 is connected with and rotated by the block shaft 16, at which time wire is being drawn through the dies 45 by the block 20. To separate the block 20 from the block shaft 16 so that the latter may continue to rotate without imparting movement to the block and to actuate the brake mechanism, 20 the treadle 26 will be disengaged from the shoulder 34 and the same is drawn upwardly by the spring 35. My improved mechanism is designed to provide means for disengaging this treadle from the shoulder 25 so that the results above indicated may be obtained. This mechanism comprises a rod 47 journaled in the bearings 48 mounted on fixed parts, arms 49 mounted on said rod 47 and connected by a rod 50, a lever 30 51 fixed on the rod 47, bell crank lever 52 mounted on the stud 53 in the front plate 29, a turn buckle connection 54 between the levers 51 and 52, and a screw 55 threaded through one arm of the lever 52, the end of 35 which engages one side of the treadle 26. The spring 56 holds the rod 50 in its outermost position, this being determined by the stop screw 57 threaded in the table 10 and engaging the outer end of the lever 51. By 40 reason of the turn-buckle connection 54 between the levers 51 and 52, the relative position of the parts may be varied. That portion of the rod 47 between the bearing 48 may be omitted if desired. If the rod 50, 45 which it will be noted, may be operated at any point along the length of the machine is pushed toward the table 10, either by accident or design, the lever 52 will oscillate upon the stud 53 and the end of the screw 50 55 will push the treadle bar 26 away from the shoulder 34, which then moves up vertically in the slot 28 by the action of the spring 35 and the rotation of the block is stopped and the brake mechanism is applied 55 to facilitate this stopping operation. As soon as the pressure is released from the rod 50 it will return to its normal outermost position by the action of the spring 56.

There are minor changes and alterations 60 65 that can be made within my invention, aside

from those herein suggested, and I would therefore have it understood that I do not limit myself to the exact construction herein shown and described, but claim all that falls fairly within the spirit and scope of the 70 appended claims.

Having described my invention, what I claim as new and desire to secure by Letters Patent, is:

1. In a machine of the character described, 75 the combination with a rotary shaft; of a block having a make and break connection therewith; lever means for initiating the action of connection; and means for actuating said lever mechanism so as to break 80 the connection between said shaft and block, said mechanism comprising a member extending the length of said machine, a member having movement in the path of said lever when in its operative position, and 85 means actuated by the first mentioned member for tripping said lever.

2. In a machine of the character described, the combination with a rotary shaft; of a block having a make and break connection 90 therewith; and means for actuating said make and break connection at any point along the length of said machine.

3. In a machine of the character described, the combination with a rotary shaft; of a 95 block having a make and break connection therewith; a brake mechanism for retarding the motion of said block; and means actuated at any point along the length of said machine for actuating both said make 100 and break connection mechanism and said brake mechanism.

4. In a machine of the character described, the combination with a rotary shaft; of a block having a make and break connection therewith; lever means for initiating the action of said make and break connection; a member extending substantially the length 110 of said machine; and a connection between said member and lever means whereby the movement of the former will actuate the latter and initiate the stopping of said block.

5. In a machine of the character described, the combination with a rotary shaft; of a 115 block having a make and break connection therewith; a brake mechanism for retarding the rotation of said block; lever means for initiating the action of said connection; a member extending substantially the length 120 of said machine; and an operative connection between said member and said lever means whereby the movement of the former will actuate the latter and initiate the stopping of said block and the action of said 125 braking mechanism.

6. In a machine of the character described, the combination with a rotary shaft; of a block having a make and break connection therewith; lever means for initiating the 130

- action of said connection; a member movable in the path of said lever means when in one of its positions to release it therefrom; a member extending substantially the length 5 of said machine; and an operative connection between said two members whereby movement of the latter will be transmitted to the former and through it to said lever means.
- 10 7. In a machine of the character described, the combination with the block; of means for rotating the same, a rock member extending along one side of the machine, and an operative connection between said rock 15 member and the means for rotating the block.
8. In a machine of the character described, the combination with a rotary shaft; of a
- block having a make and break connection therewith; lever means for initiating the 20 action of connection; means for holding said lever means in position to maintain a constant connection between said shaft and block; a trip lever mounted so as to disengage said lever from its holding means 25 when actuated in one direction; a member extending along the front of said machine; and an operative connection between said member and trip lever, whereby movement thereof in one direction will, through said 30 trip lever, break the connection between said shaft and block.

In testimony whereof, I have hereunto affixed my signature.

WILLIAM D. PIERSON.
